(57) CLAIM

The ornamental design for rings for holding the connections of the connectors, as shown.

DESCRIPTION

FIG. 1 is a front elevational view of rings for holding the connections of the connectors showing my new design; FIG. 2 is a top plan view thereof;

FIG. 3 is a right side elevational view thereof;

FIG. 4 is a left side elevational view thereof;

FIG. 5 is a rear elevational view thereof; and

FIG. 6 is a bottom plan view thereof.

FIG. 7 is a front and top perspective view thereof;

FIG. 8 is a rear and top perspective view thereof;

FIG. 9 is a front and bottom perspective view thereof; and,

FIG. 10 is a rear and bottom perspective view thereof.

The broken line shown in the drawing views represents unclaimed environmental only and forms no part of the claimed design.
